(57) CLAIM

The ornamental design for a jacket, as shown and described.

DESCRIPTION

FIG. 1 is a right front perspective view of a jacket according to the present design;

FIG. 2 is a front view thereof;

FIG. 3 is a right side view thereof;

FIG. 4 is a left side thereof; and,

FIG. 5 is a back view thereof.

The even broken lines represent parts of the jacket that form no part of the claimed design.

The long and short broken lines represent the boundaries of the claim and form no part thereof.

The stipple shading on the claimed portion depicts the contour of the pockets.

1 Claim, 5 Drawing Sheets
